CHARLES McKEE III

UNITED STATES PATENT OFFICE

WILLIAM W. WALLACE, OF CHICAGO, ILLINOIS; LILLA B. WALLACE ADMINISTRATRIX
OF SAID WILLIAM W. WALLACE, DECEASED

BRICK SETTER

Application filed August 25, 1930. Serial No. 477,650.

This invention relates to a brick setter and more particularly to the mechanism for operating the brick clamps on the fingers and elevating the same.

5 The invention comprises the novel structure and combination of parts hereinafter described and more particularly pointed out and defined in the appended claims.

In the accompanying drawings which illustrate a preferred form of this invention and in which similar reference numerals refer to similar features in the different views;

10 Figure 1 is a front elevational view of a brick setter involving this invention;

15 Figure 2 is a sectional view upon the line II-II of Figure 1; and

Figure 3 is a side elevational view of the brick setter.

Referring to the drawings, there is shown 20 a frame comprising the finger beam 1 from which the fingers 2 extend that carry the brick clamps (not shown) as is well known in the art. The brick clamps are operated by rods 3 (Figure 3) which are pivoted to 25 crank collars 4 rotatably mounted upon rods 5 and actuated by spring controlled rods 6 which extend through a lifting bar 7 which is attached to yokes 8. Only a few of the rods 6 are shown. This mechanism has not 30 been fully illustrated as it is old and well known in the art and forms no part of this invention, except as it may cooperate therewith.

The invention concerns itself more directly with the means for elevating the lifting bar 7 for applying the clamps and for elevating the load. To this end, the yokes 8 are pivotally connected to intermediate parts of levers 9 which are pivoted at their outer ends to pivots 9^a carried by brackets 10 secured to the diagonal struts 11 of the frame of the machine. The inner ends of the levers 9 are pivotally connected to short links 12 which in turn are pivotally attached intermediate the ends of a lifting bar 13 which extends through slots in guide members 14 extending from the vertical posts 15 of the frame-work.

The ends of the lifting bar 13 are pivotally attached to hollow link members 16 by

means of the pivot pins 16^a. A rod 17 (Figure 2) slidably extends into each hollow link member and is adapted to be connected thereto by a connecting pin 18 (Figure 2). These connecting pins 18 are pivoted in the bifurcations of arms 19 which are firmly secured upon an operating shaft 20 journaled in bearings 21 upon the members 16, and in bearings 22 upon the transverse angle frame member 23 which is connected to brackets 23^a extending from the diagonal struts 11. This shaft 20 is provided with an operating handle 24 whereby the same may be rotated to simultaneously withdraw the pins 18 and disconnect the rods 17 from the link members 16, a feature which may be desirable in some instances; for example, when a load of brick is deposited upon a wagon or platform, the disconnection of the pins 18 will remove all tendency to again grip 70 the bricks when the apparatus is removed and returned to the pile for another load.

The upper ends of the rods 17 embody adjustable screws 25 which are connected with clevises 26 suspended from the forward ends of levers 27. The rear ends of the levers 27 are pivoted to rearwardly extending arms 28 on the posts 15, and intermediate of their ends they are pivoted to levers 29, (Figure 3). The forward ends of the levers 29 are pivoted to lugs 30 on the posts or uprights 15. The rear ends of the levers 29 are connected to links 31 which in turn are connected to a turn table 32. The forward portions of the levers 27 are also connected 80 by links 33 with said turn table.

The aforementioned levers 9 are normally forced downwardly to release the brick clamps by means of coil springs 34. To this end a saddle member 35 straddles each lever 9. A guide pipe 36 extends upwardly from each saddle 35 for guiding the spring 34. An adjustable rod 37 slidingly fits in each guide pipe 36. The upper ends of the rods 37 are adjustably connected to bracket 23^a 95 by means of the nuts 38.

The brackets 10 and 23^a are connected by brace rods 39 as shown in Figure 3 to strengthen and give proper support to the same. The uprights 15 are also braced by

interior struts 40. The frame of the machine may, however, be constructed in any suitable manner.

It will be noted that the system of levers 5 27 and 29 will lift the load in balanced and even position without any tilting thereof, and that the lifting mechanism may be disconnected from the clamp applying mechanism at any desirable time.

10 I am aware that many changes may be made and numerous details of construction may be varied through a wide range without departing from the principles of this invention, and I, therefore, do not purpose limiting the patent granted hereon otherwise than necessitated by the prior art.

15 I claim as my invention:

20 1. In a brick setter, a finger frame including a pair of uprights having parallel arms, brick clamp operating mechanism, a pair of levers connected to said mechanism and to said arms, a second pair of levers connected to said uprights and pivoted intermediate their ends to said first pair of levers, 25 a turn table and links connecting said levers and turn table.

25 2. In a brick handling machine, a frame, lifting levers pivoted to said frame, lifting fingers carried by said frame, brick clamps operating mechanism, a pair of links depending from said levers, a pair of links extending upwardly from said brick clamps operating mechanism, a transversely extending shaft carried by said last mentioned 30 links, crank arms secured to said shaft, and locking pins carried by said crank arms for locking the pairs of links together.

35 3. In a brick handling machine, a frame including lifting fingers, brick clamps operating mechanism, levers connected to said frame, a pair of depending links on said levers, a pair of upstanding links on said mechanism, said depending and upstanding links having apertures adapted to be 40 brought into registry, a transverse shaft carried by one pair of links, crank arms on said shaft, pins carried by said crank arms for engaging in said apertures and means for rotating said shaft.

45 50 In testimony whereof I have hereunto subscribed my name at Chicago, Cook County, Illinois.

WILLIAM W. WALLACE.
